UNITED STATES PATENT OFFICE.

BERNARD S. D. S. MARTIN, OF McPHERSON, KANSAS.

STORM-CURTAIN FOR VEHICLES.

SPECIFICATION forming part of Letters Patent No. 741,265, dated October 13, 1903.

Application filed October 27, 1902. Serial No. 128,874. (No model.)

To all whom it may concern:

Be it known that I, BERNARD S. D. S. MARTIN, a subject of the King of Great Britain, residing at McPherson, in the county of McPherson and State of Kansas, have invented certain new and useful Improvements in Storm-Curtains for Buggies and Similar Vehicles, of which the following is a full and complete specification, such as will enable those skilled in the art to which it appertains to make and use the same.

The object of this invention is to provide an improved means for connecting a storm-curtain with a buggy or similar vehicle whereby the curtain may be conveniently and securely placed in position for use whenever desired and also easily detached and folded, so as to be placed beneath the buggy-seat or in any suitable receptacle.

20 The invention is fully disclosed in the following specification, of which the accompanying drawings form a part, in which the separate parts of my improvement are designated by suitable reference characters in each of the views, and in which—

Figure 1 is a front view of the top portion of a buggy provided with my improvement, one-half of the storm-curtain being in position; Fig. 2, a side view thereof; Fig. 3, a 30 perspective view of one side of the storm-curtain frame or support; Fig. 4, a section on the line 4 4 of Fig. 1; Fig. 5, a sectional front view of a part of the storm-curtain frame or support; Fig. 6, a side view of a part of the 35 device shown in Fig. 5; Fig. 7, a perspective view of a clamp which I employ for connecting the curtain with the frame or support thereof, which latter is in practice connected with the hood of the buggy; and Fig. 8, a partial section on the line 8 8 of Fig. 2.

In the drawings forming part of this specification, reference being made to Figs. 1 and 2, I have shown at *a* an ordinary buggy-body having a dashboard *a* and a seat *a* and provided in the usual manner with a hood *a*, having the usual side bars *a* and a front top hood-bar *a*, said hood and side bars being so connected as to be raised into the position shown in Fig. 2 or lowered backwardly, as 45 desired, in the usual manner.

In the practice of my invention I provide a

storm-curtain *b*, which may be composed entirely of one part or of two or more parts, and if composed of two or more parts said curtain will preferably be divided centrally or vertically, as shown in Fig. 1, or it may consist of a central portion and two side portions, as will be readily understood. I also provide a storm-curtain frame which is adapted to be connected with the buggy-top, as hereinafter 55 described, and with which the curtain is adapted to be connected, said curtain and frame being also adapted to be detached from the buggy-top and folded compactly together, so as to be placed beneath the buggy-seat or 60 in any suitable receptacle. The curtain-frame comprises a top rod *c* and side rods *d*, and the top rod *c* is provided with downwardly directed and curved end members *c*, formed separately therefrom and connected 65 therewith by means of detachable coupling-sections *c*, two of which are shown in Figs. 1 and 5, these coupling-sections being connected one with another and being also connected with the parts *c* and *c* by means of corresponding 70 sockets and socket-pins with which said parts are provided and set-screws *c*, the object of this construction being to provide means whereby the top rod *c* of the curtain-frame, or the length thereof, may be adjusted so as 75 to conform to buggy-tops of different widths, and the end members *c* of the top rod *c* may be formed so as to adapt said parts to the hoods of buggy-tops the curves of which at the sides vary. The end members *c* of the 80 rod *c* are also provided at their lower ends with detachable parts *c*, connected by means of sockets and pins, with which said parts are provided, and the set-screws *c*, and by means of this construction the parts *c* may be lowered 85 or adjusted, so as to adapt the apparatus to different styles of buggy-tops in which the depths of the side portions of the hood vary, and with each of the parts *c* is pivotally connected, as shown at *c*, a hanger *c*. The side 90 rods *d* are composed of two parts *d* and *d*, hinged together at *d*, so as to swing inwardly or in the manner of an ordinary elbow-joint, and the upper part *d* at each side is provided with an inwardly-directed member *d*, which 95 passes through the corresponding hanger *c*, and the lower part *d* is provided at its lower 100

end with a detachable member d^5 , having a pin which enters a corresponding socket in said part d^3 and is made vertically adjustable therein by means of a set-screw 5^a . The detachable member d^5 of the part d^3 is provided with an inwardly-directed handle d^6 and at its lower end with a fork d^7 , which rests on the pin or arm d^8 , with which the side bars a^5 of the buggy-top are connected in the usual manner. I also provide in the form of construction shown clamps or holders e for connecting the top rod c of the curtain-frame with the hood of the buggy, which are preferably three in number and one of which is placed at the center of said rod and one at each side, and each of these clamps or holders consists of a plate e^2 , having a top portion e^3 , adapted to overlap the front of the hood-rest on the cloth or leather cover e^4 over the front bar e^5 , and said plate e is provided with an arm e^6 , pivoted thereto at e^7 , and secured to the plate e above the pivotal point e^7 of the arm e^6 is a shoulder or rest e^8 , above which is a spring e^9 , which is secured to the arm e^6 and serves to pull it upwardly against the bar e^5 . Below the pivotal support e^7 of the arm e^6 the plate e^2 is provided with another spring 9^e , which bears on the lower side of said arm and forces it upwardly, and said arm is provided at its rear end with a downwardly-directed finger or handle piece g , by which it may be pulled downwardly. The plate e^2 is also provided with a backwardly and downwardly directed finger-piece g^2 , which may be grasped in the operation of pulling downwardly on the finger or handle piece g , and at the lower edge of the plate e^2 is a hook g^3 upon which to hang the overlap of the curtain in windy weather, and the entire clamp or holder is preferably provided with a front plate g^4 , which covers that portion of the storm-curtain in which or to which the clamp or holder is secured, and this plate may be ornamented, if desired, and in practice the curtain may be slitted or provided with an opening whereby the clamps or holders e may be manipulated.

In the normal position of the side rods d of the curtain-frame said rods set outside of the framework of the hood or outside of the bars a^5 and the side curtains secured thereto, as shown in Fig. 2, and the inwardly-directed parts or arms d^4 at the upper ends of the side rods d pass inwardly transversely in front of the side bars a^5 of the buggy-top and through the hangers c^8 and are then curved backwardly and outwardly to form a hook g^5 , which engages the front bar a^5 of the buggy-top, this construction being shown in detail in Fig. 3 or in the place of which a clamp may be employed.

Secured to the front of the buggy-body a is a plate h , having outwardly-directed spring-arms h^2 , above which are shorter outwardly-directed spring-arms h^3 , and these spring-arms are adapted to serve as connections for spring-fastening devices h^4 , by which the cur-

tain or separate parts thereof are held in position at the front, and the plate h is provided with an upwardly-directed socket member h^5 , designed to hold a whip.

In order to connect the curtain b or the parts thereof with the curtain-frame or the rods thereof, I provide clamps i , consisting of parallel plates or jaw members i^2 , which may be of any desired length and which are connected by semicircular, segmental, or elliptical springs i^3 , and in practice the edge or edges of the curtain or the separate parts thereof are passed around the rods c and d of the curtain-frame, as clearly indicated in Fig. 8, and the clamps or holders i are then pressed thereover or passed thereonto, as shown in Fig. 8 and as indicated in Figs. 1 and 2, and by this means the curtain or the parts thereof are securely held in the connection with the curtain-frame or the rods thereof.

If preferred, the edges of the curtain or the parts thereof may be secured in the clamps i and afterward connected with the curtain-frame or the rods thereof, and this connection may be made in any desired manner, or the plates or jaws i^2 of the clamps i may be provided with serrations or teeth which will engage the curtain or the parts thereof and keep the same from slipping. As shown in Fig. 8, the rods d and c are made irregular in cross-section, being thicker at one side than the other, and these rods are shown in other views as circular in form; but I prefer the form shown in Fig. 8.

As the curtain-frame is thus made it will be seen that the length of the top rod c may be adjusted by taking out one or more of the parts c^3 , and said rod may thus be made of any desired length. The end portions c^2 may be turned therein or adjusted longitudinally, and the hangers c^8 are adapted to swing in a vertical plane, and the side rods d^2 may thus be folded upwardly at c^7 , and the parts c^5 may be so turned as to permit the side rods d to fold transversely of the upper portion of the curtain. The side rods d may also be folded centrally at d^4 , and the entire curtain and the frame thereof may thus be taken off and compactly folded whenever desired and placed beneath the seat of the buggy or in any suitable receptacle, and the said curtain and curtain-frame may be connected with the buggy-top whenever desired.

The curtain may be provided at both sides with view-openings and also with openings through which to pass the reins, if desired; but these details form no part of this invention.

It will be apparent that the length of the side rods d may be adjusted by means of the parts d^5 , and the handles d^6 , one of which is at each side of the buggy-top, are employed for the purpose of adjusting or placing in position the separate parts of the hood-frame, and the object of the arms e^6 at the top of the hood-frame is to facilitate this operation, said arms being pulled downwardly or de-

pressed whenever it is necessary to connect the curtain-frame with the top of the buggy or remove said frame therefrom.

Having fully described my invention, what I claim as new, and desire to secure by Letters Patent, is—

1. A storm-curtain frame for buggy-tops, comprising a top rod having downwardly-directed end members, means whereby said rod 10 may be made shorter or longer, adjustable parts connected with the lower ends of the end members, hangers hinged to said adjustable parts, and side rods the upper ends of which are directed inwardly and passed 15 through said hangers, and the lower ends of which are provided with forks adapted to engage the pins or arms with which the side bars of the buggy-top are pivotally connected, said side rods being composed of two parts hinged 20 together, substantially as shown and described.

2. A storm-curtain frame for buggy-tops, comprising a top rod having downwardly-directed end members, means whereby said rod 25 may be made shorter or longer, adjustable parts connected with the lower ends of the end members, hangers hinged to said adjustable parts, and side rods the upper ends of which are directed inwardly and passed 30 through said hangers and the lower ends of which are provided with forks adapted to engage the pins or arms with which the side bars of the buggy-top are pivotally connected, said side rods being composed of two parts hinged 35 together, and the lower sections of said side rods being also composed of separate adjustable parts, substantially as shown and described.

3. A storm-curtain frame for buggy-tops, 40 comprising a top rod having downwardly-directed end members, means whereby said rod may be made shorter or longer, adjustable parts connected with the lower ends of the end members, hangers hinged to said adjustable parts, side rods the upper ends of which 45 are directed inwardly and passed through said hanger and the lower ends of which are provided with forks adapted to engage the pins or arms with which the side bars of the 50 buggy-top are pivotally connected, said side rods being composed of two parts hinged together, and clamps whereby the curtain is connected with the rods of said frame, substantially as shown and described.

4. A storm-curtain frame for buggy-tops, 55 comprising a top rod having downwardly-directed end members, hangers hinged to the lower ends of said end members, and side rods having inwardly-directed upper ends which pass through said hangers and are provided 60 with outwardly-directed hooks, said side rods being composed of two members hinged together, and the lower members being provided with adjustable forks, substantially as shown and described.

5. A storm-curtain frame for buggy-tops, comprising a top rod having downwardly-directed end members, hangers hinged to the lower ends of said end members, side rods having inwardly-directed upper ends which 70 pass through said hangers and are provided with outwardly-directed hooks, said side rods being composed of two members hinged together, and the lower members being provided with adjustable forks, and means for connecting the curtain with said frame and the top rod of said frame with the hood of the buggy-top, substantially as shown and described.

6. In a device of the class described, a clamp or holder comprising a front plate and arm 80 hinged to the back of said plate and provided with springs which are connected with said plate and by which it is held in a raised position, said arm being provided with downwardly-directed handle-pieces, substantially 85 as shown and described.

7. The herein-described means for connecting the top rod of a storm-curtain frame with the front top bar of the hood of a buggy-top comprising a clamp composed of a plate provided at its upper edge with a backwardly-directed member, an arm hinged to said plate, and springs connected with said plate and said arm for holding the upper end of said arm against said bar, said bar being also provided 95 with an opening through which the rod of the curtain-frame passes and also with a downwardly-directed handle-piece, substantially as shown and described.

In testimony that I claim the foregoing as 100 my invention I have signed my name, in presence of the subscribing witnesses, this 17th day of October, 1902.

BERNARD S. D. S. MARTIN.
